SUMNER WILTSE, OF DETROIT, MICHIGAN, ASSIGNOR TO WILTSE APPLIANCE COMPANY, A CORPORATION OF MICHIGAN

PRIMING DEVICE

Application filed September 1, 1927. Serial No. 216,827.

This invention relates to means for priming pumps and relates particularly to means for priming mechanical fuel pumps such as are commonly used in connection with internal combustion engines, the principal object being the provision of a simple and economical priming device for pumps of the type described.

Another object is to provide, in combination with an internal combustion engine, a passage between the carburetor float bowl and the intake manifold, means being provided for cutting off the suction imposed by the manifold on the float chamber through the passage.

A further object is to provide, in combination with an internal combustion engine provided with a mechanically actuated fuel pump, a carburetor provided with an air tight bowl into which the pump is adapted to discharge fuel, a passage being provided connecting the interior of the carburetor bowl with the intake manifold above the throttle and a valve being positioned within the passage and operable to transmit the suction within the intake manifold to the carburetor bowl and thence to the fuel pump, and also operable to close the passage to the intake manifold and open the passage to the air whereby atmospheric pressure will be transmitted to the carburetor bowl.

The above being among the objects of the present invention, the same consists in certain features of construction and combinations of parts to be hereinafter described with reference to the accompanying drawing, and then claimed, having the above and other objects in view.

In the accompanying drawing which illustrates a suitable embodiment of the present invention, and in which like numerals refer to like parts throughout the several different views,—

Fig. 1 is a more or less diagrammatic side view of an internal combustion engine positioned below the hood of a motor vehicle.

Fig. 2 is an enlarged vertical sectional view taken centrally through the carburetor shown on the engine in Fig. 1.

Fig. 3 is a face view of the valve mecha-

nism shown mounted on the instrument board in Fig. 1 and connected in the piping between the carburetor and intake manifold.

Fig. 4 is a sectional view of the valve mechanism taken on the line 4—4 of Fig. 3. 55

Fig. 5 is a face view of the back member employed in the valve mechanism shown in Fig. 4.

Fig. 6 is a face view of the rotatable member employed in the valve construction of 60 Fig. 4.

When mechanically driven fuel pumps are employed for conducting fuel to the carburetors of internal combustion engines, particularly when the carburetor and the pump are positioned above the level of the fuel in the fuel supply tank as is the usual case in motor vehicle constructions, the fuel in the lines from the carburetor to the fuel supply tank often drains back into the fuel supply tank upon stopping of the engine and leaves such passage filled with air. Unless the pump in such case is not worn or unless some precautions are taken to prevent the fuel from flowing back to the supply tank, it is often difficult and sometimes impossible for the pump to regain its prime without some aid. Although the pump might often regain its prime after running the engine for several minutes with the electric starter, such practice is not only very inconvenient, but causes loss of charge of the storage battery and often causes damage to the same. 75 80 85

By the present invention I provide a means whereby when such mechanically driven fuel pump loses its prime, the same may be re-established in a quick and effective manner.

Referring to the accompanying drawing, in order to better illustrate the present invention, I show in Fig. 1 an internal combustion engine designated generally as 10 positioned below the hood 11 of a motor vehicle and substantially in front of the dash 12 thereof. The engine 10 is provided with a conventional intake manifold 13 and carburetor designated generally in Fig. 1 as 14. A mechanically driven fuel pump 15 provided with a pair of intermeshing spur gears 16 and suitably driven from the cam shaft of the 100

engine 10 or by some suitable means is connected by the tubing 17 with a fuel supply source such as a tank (not shown) mounted on the rear of the vehicle and below the level of the pump 15. Referring to Fig. 2 it will be seen that the carbureter is of conventional construction having a float bowl or chamber 18, a vaporizing nozzle 19, venturi 20, air passage 21 and throttle 22. The float chamber 18 is provided with a cover 23 secured thereto in such a manner as to seal it against the leakage of air. A float valve 24 secured to the arm 25 which in turn is pivotally mounted at 26 to the under side of the cover 23 operates the needle valve 27 to close the passage 28 against the flow of fuel from the pump 15 through the tube or pipe 29. A second tube or pipe 30 is connected by the connection 31 and opening 32 in the cover 23 to the interior of the float bowl 18. The tube 30 extends from the bowl 18 through the dash 12 and to the valve mechanism indicated generally by the numeral 33 in Fig. 1 which is mounted on the instrument board 34 of the vehicle. A third tube 35 connects the valve mechanism 33 with the intake manifold 13.

The valve mechanism as indicated in Figs. 3 to 6 inclusive comprises a casing 36 within which is received a disc 37, a disc-like rotor 38, and a back plate 39. A handle 40 is provided with a shank 41, the latter rotatably projecting through the face of the casing 36 and through the disc 37, and its squared portion 42 being received within the corresponding squared opening 43 in the rotor 38. The squared portion 42 terminates in a stud 43 which is received within the enlarged central opening 44 in the back plate 39 and receives thereon the nut 45 which secures the handle 40 in place. An open cap 46 is threadably received on the rear of the casing 36 and is provided with a resilient gasket 47 between the same and the back plate 38 which serves to clamp all of the members in operative position and prevents rotation of the back plate 39. The back plate 39 as shown in Fig. 5 is provided with three openings 48, 49 and 50 disposed about the center thereof in spaced relationship. The rotor 38, as shown in Fig. 6, is provided with a curved slot 51, the center of which is distances from the center of the rotor 38 an amount corresponding with the distance of the openings 48, 49 and 50 from the center of the back plate 39 so as to match the same when turned to the proper rotative positions. The slot 51 is of a length sufficient to extend between the openings 48 and 49, or 49 and 50 when turned to the proper rotative positions. The tube 30 from the carburetor is connected by the connection 52 to the opening 49, and the opening 48 is connected by the connection 53 and by the tube 35 to the intake manifold 13. The opening 50 communicates at the rear of the back plate 39

directly with the atmosphere, or a connection 54 may be provided for the same for connection to a tube or pipe 55 which may be extended down and connected to the carbureter at a point adjacent the air inlet thereof 70 so that in cases where the handle 40 is turned to block the tube 35 any fuel vapors tending to pass off from the fuel within the carbureter bowl 18 through the pipe or tube 30 will be lead back through the tube 55 and be discharged into the interior of the carbureter and will be drawn into the engine cylinders and burned. The tube 55 is preferably connected to the carbureter in such a manner that the suction within the same has little or 80 no effect on reducing the pressure within the carburetor bowl and yet is placed in such a manner that any fuel vapors passing out of the pipe 55 will be drawn into the carbureter with the air entering the same. When the 85 rotor 38 is rotated by the handle 40 so as to cause the slot 51 to connect the opening 48 and 49, it will be apparent that the tubes 30 and 35 are thus connected together so that any suction in the intake manifold 13 is 90 transmitted to the interior of the bowl 18, and when the handle 40 is turned to move the slot so as to connect the openings 49 and 50, it will be apparent that the opening 48 and consequently the tube 35 is closed against the 95 passage of air and the interior of the bowl 18 is communicated with the atmosphere through the tube 30 the opening 49, slot 51 and opening 50 where no tube 55 is employed, and through the tube 55 when the same is 100 employed.

In practice when it is found that the pump 15 has lost its prime, the handle 40 is moved to bring the slot 51 over the openings 48 and 49, the electric starter is then operated causing the engine to revolve thus creating a suction in the intake manifold 13 and this suction is transmitted through the pipe 35, opening 48, slot 51, opening 49, and pipe 30 to the interior of the carbureter bowl 31, and from the carbureter bowl 31 through the opening 28 and tube 29 to the pump 15 and thence through the tube 17 to the source of fuel supply. The suction in the intake manifold is therefore transmitted to the fuel supply tank and tends to suck the fuel into the pump 15. As soon as the fuel is thus sucked into the pump 15, the pump is again primed and begins to pump fuel and at such time the handle 40 may be swung around so as to 115 connect the openings 49 and 50 by the slot 51, thereby admitting air under atmospheric pressure to the interior of the carbureter bowl 18 and closing the pipe 35. Should the float 24 of the carbureter bowl at the time 120 the engine is started be sufficiently high to prevent the suction within the bowl 18 from being transmitted to the pump 15 past the needle valve 27, if the pump has lost its prime at such time, the level of fuel within the bowl 125 130

18 will quickly drop upon starting of the engine sufficiently to unseat the needle 27 and therefore break its seal. It is important when the carbureter bowl 18 is sealed against leakage of air that some means be provided, as in the present case, for the introduction of air under atmospheric pressure to the carbureter bowl in order that it may function properly, and although I have provided a construction in the present invention wherein the carbureter bowl is sealed at the bowl itself against the introduction of air, it will be apparent that the usual vent may be provided in the same and the pipes 30 and 35 be made of sufficient size so as to suck the air out of the bowl 18 at a greater rate than the vent is capable of supplying the same, thereby creating a sufficient suction in the bowl 18 which may be transmitted through the pipes 29 and 17 to suck the fuel from the supply tank into the pump, and in such a case it is only necessary to provide a simple shut-off cock between the pipes 30 and 35, but I prefer to use the construction indicated inasmuch as I am able to obtain the greater suction on the fuel and therefore a quicker priming action on the pump 15.

Although I have shown a particular form of valve between the tubes 30 and 35, it is to be understood that the valve shown is merely for the purpose of illustration and that any suitable valve mechanism may be employed at this point, and it will also be understood that the extending of the valve itself to the instrument board 34 of the vehicle is merely a matter of convenience, and it may be positioned between a pair of short pipes extending directly between the carbureter bowl 18 and the intake manifold 30 and may be operated, if desired, by a rod or other device extending from the instrument board 34 to such valve, and these and other formal changes may be made in the specific embodiment of the invention described without departing from the spirit or substance of the broad invention, the scope of which is commensurate with the appended claims.

What I claim is:

1. In combination with an internal combustion engine having an intake manifold, a carbureter connected thereto, and a mechanically driven pump for delivering fuel to said carbureter, means for priming said pump comprising a passage exterior to said carbureter between the float bowl thereof and said intake manifold, and means in said passage for closing the same.

2. In combination with an internal combustion engine having an intake manifold and a carbureter provided with a float bowl, a throttle valve for said carbureter, mechanical means for supplying fuel to said float bowl, a passage connecting said bowl above the normal fuel level therein with the intake manifold above said throttle valve, and valv-

ular means in said passage for closing or opening the same.

3. In combination with an internal combustion engine having an intake manifold and a carbureter provided with an air tight bowl, a throttle valve for said carbureter, mechanical means for elevating fuel to said carbureter, a passage connecting said bowl above the normal fuel level therein with the intake manifold between said throttle valve in the engine cylinders, valvular means in said passage for closing or opening the same, and means for admitting air under atmospheric pressure to said bowl.

4. In combination with an internal combustion engine having an intake manifold and a carbureter provided with an air tight float bowl, mechanical fuel supplying means connected with said float bowl for supplying fuel thereto, valvular means, an air passage connecting said float bowl with said valvular means, and an air passage connecting said intake manifold with said valvular means, said valvular means being operable to connect said passages when in one position and operable to shut off the last mentioned passage and opening the first mentioned passage to the atmosphere when in another position.

5. In a motor vehicle, in combination with the internal combustion engine thereof having an intake manifold and a carbureter connected thereto, a pump for supplying fuel to said carbureter, an air passageway connecting the float bowl of said carbureter with said intake manifold, and valvular means in said passageway for opening or closing the same manually operable from the instrument panel of said vehicle.

6. In a motor vehicle, in combination with the engine and instrument panel thereof, an intake manifold, a carbureter connected thereto, a mechanically driven fuel pump for discharging fuel into the float bowl of said carbureter, and means for priming said pump comprising valvular means supported from said instrument panel, a pipe connecting the bowl of said carbureter with said means, and a pipe connecting said intake manifold with said means, said means being operable to connect said pipes or to shut one off from the other thereof.

7. In combination with an internal combustion engine having an intake manifold and a carbureter provided with an air-tight float bowl, a pump for supplying fuel to said float bowl, valvular means, an air passage connecting said float bowl with the said valvular means, an air passage connecting said intake manifold with said valvular means, said valvular means being operable to connect said passages when in one position and operable to shut off the last mentioned passage and connect the first mentioned passage with the atmosphere at a point adjacent the air inlet of said carbureter.

8. In a motor vehicle, in combination with the engine and instrument panel thereof, a mechanically driven fuel pump for discharging fuel into the float bowl of said carburetor, and means for priming said pump comprising valvular means supported from said instrument panel, a pipe connecting the bowl of said carburetor with said means, a pipe connecting said intake manifold with said means, and a pipe connecting said means with a point adjacent the air inlet of said carburetor, said means being manually operable at will to connect said pipes in pairs.

SUMNER WILTSE.
